(57) **CLAIM**

The ornamental design for a fishing tool, as shown and described.

DESCRIPTION

FIG. 1 is a perspective view of a fishing tool according to the design herein.

FIG. 2 is a top view of the fishing tool shown in FIG. 1.

FIG. 3 is a bottom view of the fishing tool shown in FIG. 1.

FIG. 4 is a side view of the fishing tool shown in FIG. 1.

FIG. 5 is a front view of the fishing tool shown in FIG. 1.

FIG. 6 is a rear view of the fishing tool shown in FIG. 1.

FIG. 7 is a perspective view of an alternative embodiment of a fishing tool according to the design herein.

FIG. 8 is a top view of an alternative embodiment of the fishing tool shown in FIG. 7.

FIG. 9 is a bottom view of an alternative embodiment of the fishing tool shown in FIG. 7.

FIG. 10 is a side view of an alternative embodiment of the fishing tool shown in FIG. 7.

FIG. 11 is a front view of an alternative embodiment of the fishing tool shown in FIG. 7.

FIG. 12 is a rear view of an alternative embodiment of the fishing tool shown in FIG. 7.

FIG. 13 is a perspective view of a second alternative embodiment of a fishing tool according to the design herein.

FIG. 14 is a top view of a second alternative embodiment of the fishing tool shown in FIG. 13.

FIG. 15 is a bottom view of a second alternative embodiment of the fishing tool shown in FIG. 13.

FIG. 16 is a side view of a second alternative embodiment of the fishing tool shown in FIG. 13.

FIG. 17 is a front view of a second alternative embodiment of the fishing tool shown in FIG. 13; and,

FIG. 18 is a rear view of a second alternative embodiment of the fishing tool shown in FIG. 13.

The broken lines that are included in the figures of the drawings denote aspects of the tool that form no part of the claimed design.
